ARTHUR BRUCE SPERRY, OF NEW YORK, N. Y., ASSIGNOR, BY MESNE ASSIGNMENTS, TO
WESTERN ELECTRIC COMPANY, INCORPORATED, A CORPORATION OF NEW YORK.

AUTOMATIC TELEPHONE-EXCHANGE SYSTEM.

1,233,819.

Specification of Letters Patent. Patented July 17, 1917.

Application filed September 11, 1915. Serial No. 50,155.

To all whom it may concern:

Be it known that I, ARTHUR BRUCE SPERRY, a citizen of the United States, residing at New York, in the county of New York and State of New York, have invented 5 certain new and useful Improvements in Automatic Telephone-Exchange Systems, of which the following is a full, clear, concise, and exact description.

10 This invention relates to telephone exchange systems, and particularly to automatic telephone exchange systems.

It is desirable, especially in an automatic telephone exchange system, after a call has 15 been extended and the calling and called subscribers have been placed in communication with each other, that either subscriber be notified when the other hangs up his receiver and cannot be further communicated 20 with except by a new calling operation. To this end there is provided at the final connector means which operates, on the hanging up of the receiver of either party, to send a busy signal over the line conductors 25 to the remaining party. The object of the invention, therefore, is the provision of means for notifying one of the parties to a call of the hanging up of the receiver by the other party to said call.

30 The accompanying drawing shows the invention applied to an automatic telephone system, with so much of the system shown as is necessary for an understanding of the invention.

35 Assuming that subscriber A wishes to talk with subscriber B, and the call has progressed as far as the final connector shown in the figure through the intermediate 40 switch 10 (or switches), line relay 11 will be energized from battery, right winding of line relay 11, line conductor 12, through the substation apparatus of subscriber A, over line conductor 13, through the left winding of line relay 11, back to battery, 45 energizing the line relay which completes an energizing circuit for the slow-acting relay 14, which in turn completes a break point in the circuit for the rotary magnet 15.

50 The subscriber A now actuates the impulse-sending device 16 to control the connector. Each interruption of the line circuit causes a current impulse in the following circuit for the rotary magnet 15: from battery, through the winding of said rotary magnet, the arm 4 of the side switch, con-

ductor 17, armature and front contact of the slow-acting relay 14, and armature and back contact of line relay 11. Energized in multiple with the rotary magnet 15 is an escape magnet relay 18, which operates over 60 a circuit from battery, winding of said relay 18, conductor 19, armature and back contact of a slow-acting relay 20, conductor 21, conductor 17, armature and front contact of slow-acting relay 14, and armature and 65 back contact of line relay 11 to ground.

The energization of the escape magnet relay 18 completes a circuit from battery through the escape magnet 22, armature and back contact of release magnet 23, conductor 70 24, contact 25, and armature of escape magnet relay 18, conductor 26, arm 5 of the side switch, and right-hand armatures and back contacts of relay 20 and back-bridge relay 27, conductor 28 and armature, and back 75 contact of generator control relay 29, to ground.

When the necessary number of impulses from the sending device 16 have been sent over the line to select the tens digit, the line 80 relay 11 is maintained energized, resulting in a prolonged break in the circuit of both the rotary magnet 15 and the escape magnet relay 18. The deenergization of the escape magnet relay 18 causes the opening of the 85 circuit for the escape magnet 22, whereupon the side switch moves from its normal position 1 to position 2.

The subscriber A now sends the units impulses from the impulse-sending device 16, 90 intermittently deenergizing the line relay 11, as before. As the side switch is in the second position, the vertical magnet 40 is now intermittently energized, moving the brushes 34, 35 and 36 over the terminals of 95 subscribers' lines. As in the case when the tens impulses were sent, the escape magnet relay 18 is held energized and again energizes the escape magnet 22 over the circuit before traced.

When the necessary number of impulses have been sent to position the brushes 34, 35, 36 on the terminals 31, 32, 33 leading to the substation B, the escape relay 18 again becomes deenergized, resulting as before, 105 provided the line is idle, in the deenergization of the escape magnet 22.

If, however, the line to which connection is thus made is busy, terminal 31 would have been grounded and the escape magnet 22, re- 110

mains energized; since contact spring 25 makes before the ground connection over conductor 26 is broken, and a circuit is maintained for the escape magnet through the 5 busy relay 37 and its normal contact, the side switch arm 3 and the grounded terminal 31 with which the brush 34 is in contact. The busy relay thereupon closes for itself a locking circuit at its left-hand armature, 10 and at its right-hand armature connecting the busy interrupter 38 to the line conductor 12 over the conductor 39.

In case the desired line is idle, the de-energization of the escape magnet 22 moves 15 the side switch into the third position, whereupon the escape magnet 22 is again energized in a circuit from battery through the winding of said magnet, right-hand armature and back contact of release mag- 20 net 23, the arm 5 of the side switch in the third position thereof, right-hand armatures and back contacts of the slow-acting relay 20 and back-bridge relay 27, conductor 28 and armature of generator control relay 29 25 to ground. The escape magnet 22 closes a circuit from the ringing generator to the generator control relay 29, armature and front contact of escape magnet 22, conductor 41, arm 1 of the side switch in the third 30 position thereof, brush 36, contact 33, out over the line through the apparatus of sub- 35 station B, back to terminal 32, brush 35, arm 2 of the side switch in the third position thereof, to ground, thereby projecting ringing current over the line and causing the operation of the signal bell at substa- 40 tion B.

Generator relay 29 does not operate on ringing current, but when the called sub- 45 scriber removes his receiver from its switch-hook, this relay operates, attracts its armature and breaks the circuit for the escape magnet 22, whereupon the side switch moves from the third into the fourth position. In 50 the fourth position of the side switch, the subscribers are connected for conversation, and a circuit is closed from battery through right winding of back-bridge relay 27, out over the line to the substation B, back 55 through the left winding of back-bridge relay 27 to battery, energizing said relay, which attracts its armatures and closes at its right armature and front contact a circuit for slow-acting relay 20 from battery over the conductor 28 and the armature of control relay generator 29 to ground.

Should either A or B hang up his receiver at the termination of the conversation, it is desirable that the remaining subscriber 60 be informed of such hanging up so he may know that the party who hangs up first cannot be again reached unless the calling operation is repeated.

Assuming that subscriber B hangs up his 65 receiver first, this causes a break in the ener-

gizing circuit of the back-bridge relay 27 which deenergizes, breaking at its right armature and front contact the circuit for the slow-acting relay 20, which in turn de-energizes, establishing a circuit from battery 70 through the escape magnet 22, right armature and back contact of release magnet 23, conductor 24, contact 25, winding of busy relay 37, conductor 42, conductor 43, arm 5 of the side switch in the fourth position 75 thereof, right armatures and back contacts of the slow-acting relay 20 and back-bridge relay 27, conductor 28, and back contact and armature of generator control relay 29 to ground, energizing the busy relay 37. The 80 busy relay 37 is thereupon energized, closing a locking circuit for itself at its left armature, and connecting the busy interrupter 38 to the line wire 12 at its right armature and front contact. The subscriber 85 B having already hung up, is out of circuit. Subscriber A, however, being on the line, the busy signal from the interrupter 38 will be projected over the line through his sub- 90 station apparatus, and he will be notified thereby of the hanging up of the receiver by subscriber B.

If subscriber A hangs up first, the line relay 11 is deenergized, as in the case of the back-bridge relay 27, by subscriber B. The 95 relay 14 being slow-acting is not immediately deenergized, and a momentary circuit is closed from battery through the winding of escape magnet 22, right armature and back contact of release magnet 23, conductor 100 24, contact 25, winding of busy relay 37, conductor 42, conductor 45, arm 4 of the side switch in the fourth position thereof, conductor 105 17, armature and front contact of slow-acting relay 14 and armature and back contact of line relay 11 to ground, energizing as before the busy relay 37 which closes a locking circuit for itself at its left armature and connects the busy interrupter 38 to the line conductor 12, in this case projecting the busy signal to the subscriber 110 remaining on the line; that is, to subscriber B.

What is claimed is:

1. In an automatic telephone exchange system, two subscribers' stations, automatic means for connecting said subscribers' stations for conversation, and signaling apparatus intermediate thereto operated by a change in the condition of the apparatus at either station for notifying the other 120 station of said changed condition.

2. In an automatic telephone exchange system, a plurality of subscribers' stations, automatic means for connecting any two of said stations for conversation, and signaling apparatus operated by a change in the condition of the apparatus of either of the stations connected for conversation for notifying the other station of such changed condition.

3. In a telephone exchange system, a central office, two subscribers' stations, a line connecting said stations for conversation, apparatus at the central office adapted to project signaling current to either of said stations, a relay for each of the subscribers' stations and under the control thereof located at the central office, and a switching device operated by either of said relays for connecting said apparatus with the line, whereby said signaling current is projected to the remaining station.
4. In a telephone exchange system, a central office, a plurality of subscribers' stations, automatic means for connecting any two of said stations for conversation, apparatus adapted to project signaling current to either of said two subscribers' stations, and a switching device under the control of either subscriber's station for connecting said apparatus with the remaining subscriber's station.
5. In a telephone exchange system, a central office, a plurality of subscribers' stations, automatic means for connecting any two of said stations for conversation, apparatus adapted to project signaling current to either of said two stations from said central office, a switching device at the central office for connecting said signaling current with either station and adapted to be operated by either subscriber whereby said signaling current is projected to the other station.
6. In a telephone exchange system, a plurality of subscribers' stations, central office automatic means for connecting any two of said stations for conversation, and apparatus located at the central office operated upon disconnection of the telephone at either of the stations connected for conversation for signaling the other station of such disconnection.
7. In an automatic telephone exchange system, a plurality of subscribers' stations, central office selective means for connecting said stations for conversation, a source of signaling current at the central office, automatic means for connecting said source in circuit with a calling station upon test by said selective switching means of a busy wanted station, and means for rendering effective said connecting means so as to connect said source in circuit with either of the two stations, when connected for conversation, upon disconnection of the telephone apparatus at the other station.
8. In an automatic telephone exchange system, two subscribers' stations, automatic means for connecting said subscribers' stations for conversation, apparatus intermediate thereto operated by a change in the condition of the apparatus at the calling station connected for conversation for notifying the called station of the said changed condition.

In witness whereof, I hereunto subscribe my name this 8th day of September A. D., 1915.

ARTHUR BRUCE SPERRY.
